US00D515062S

(12) **United States Design Patent** (10) Patent No.: **US D515,062 S**
 Winebrenner et al. (45) Date of Patent: **** Feb. 14, 2006**

(54) **CRADLE FOR AN ELECTRONIC COMMUNICATION DEVICE**

(75) Inventors: **Jon Theron Winebrenner**, Richmond (CA); **Craig Stephen Gauld**, Vancouver (CA); **Harish Kumar Patel**, Burnaby (CA); **Michael Robert King**, Burnaby (CA); **Larry Zibrik**, Surrey (CA)

(73) Assignee: **Sierra Wireless**, Richmond (CA)

(**) Term: **14 Years**

(21) Appl. No.: **29/208,278**

(22) Filed: **Jun. 24, 2004**

(51) **LOC (8) Cl. 14-03**

(52) **U.S. Cl. D14/149; D13/108; D14/253**

(57) **CLAIM**

The ornamental design for a cradle for an electronic communication device, as shown and described.

DESCRIPTION

FIG. 1 is a perspective view of the cradle.

FIG. 2 is a front view of the cradle.

FIG. 3 is a back view of the cradle.

FIG. 4 is a left side view of the cradle.

FIG. 5 is a right side view of the cradle.

FIG. 6 is a top view of the cradle; and,

FIG. 7 is a bottom view of the cradle.

The broken line showings throughout the views are for illustrative purposes only and form no part of the claimed design.

1 Claim, 6 Drawing Sheets

FIG. 1

FIG. 2

FIG. 3

FIG. 4

FIG. 5

FIG. 6

FIG. 7
